UNITED STATES PATENT OFFICE

FRANK C. DELI, OF CHICAGO, ILLINOIS

PENCIL

Application filed April 18, 1929. Serial No. 356,233.

My invention relates to pencils and particularly to improvements in mechanical pencils.

One of the objects of my invention is to eliminate, so far as possible, the multiplicity of coordinating parts commonly found in mechanical pencils. By so doing, I have provided a pencil that is of the utmost simplicity and yet easily operable and of durable construction.

Another object of my invention is to provide means in the relatively rotating parts of a pencil that will insure a fixed frictional resistance to rotation without the use of the common interfitting relation of a metal sleeve and a non-metallic cylinder. Due to the nature of the materials and to climatic changes in different parts of the country, the interfitting rotating parts frequently become either loose or too tight. In the construction here proposed this is avoided and the frictional resistance is secured by an original distortion of the lead tube.

A further object of my invention is to provide a plunger that will function perfectly in a threaded lead tube, but being formed without cutting threads therein, thus strengthening the plunger and removing the possibility of damage thereto in the event of jamming of the lead.

The invention will be more readily understood by reference to the accompanying drawing, in which

Fig. 1 is a longitudinal sectional view of a pencil constructed in accordance with my invention;

Fig. 2 is a cross-sectional view taken on the line 2-2 of Fig. 1;

Fig. 3 is a plan view of the plunger utilized in my construction; and

Fig. 4 is a fragmentary longitudinal sectional view showing the tip extending to the head of the tube.

By reference to the drawing, it will be seen that my invention comprises the barrel 10, having a circular axial opening 12 in the lower end, which merges into a non-circular portion 13. A cap 14 and an eraser 15 close an upper axial opening 11.

The circular opening 12 is adapted to re-

ceive the bowed spirally grooved lead tube 16 having a non-metallic tip 17 formed thereon abutting the lower end of the barrel. As shown in the drawing the part 17 is molded around the tube 16. The lower pointed extremity of the tube 16 is split to allow for the commercial variation in the leads used and to provide the necessary friction to prevent the lead from dropping out. In the form shown in Fig. 4, the tip extends to the end 60 of the tube, but experience has shown that the expansion of the split tube is so small that the progress of a lead therethrough is not materially impeded by confining the tip.

The plunger 18 is provided with the flattened portion 19 and the bends or laterally deflected portions 20 and is adapted to be received in the tube 16, the bends 20 having the same pitch as the grooves in the tube. The flattened portion 19 is received within the non-circular opening 13. As best seen in Fig. 1 the space 21 is provided between the upper end of the tube 16 and the end of the circular opening 12. This provides a neutral zone or safety space, as hereafter described.

In operation a lead 22 is inserted in the upper end of the tube 16 and the plunger 18 is screwed into the tube a short distance. The tube and plunger may then be inserted into the barrel, the flattened portion 19 of the plunger occupying the non-circular portion 13 of the barrel. The barrel being then rotated with the tip held securely against movement, or vice versa, the plunger will be forced forward in the threaded tube 16, thus advancing the lead. It is obvious that when the portion 19 emerges from the non-circular portion 13 into the circular portion 12, further rotation of the tip or barrel will not advance the plunger. This, therefore, provides a safety zone, and prevents injury or damage to the pencil when the lead therein has been used.

The tip and tube are suitably frictionally confined in the circular opening 12 by reason of a slight initial bowing of the tube 16 from end to end. As the tube is forced into the circular axial opening it is straightened and thus does not interfere with the operation of the plunger and lead. However, the

permanent set in the tube causes it to bind in the axial opening and results in frictional engagement with the walls of the opening. This provides the necessary frictional resistance to prevent the tube and plunger from dropping out of the lower end of the pencil.

The use of the bends 20 on the plunger 18 permits the use of a plunger of much less cross-sectional area than if screw threads were cut therein. This therefore serves to 10 strengthen the plunger and reduce the weight of the pencil.

I claim:

1. In combination, a pencil body having an axial opening, one portion of which is non-circular in cross-section, the lower end of the body being tapered, a slightly bowed threaded tube and a plunger adapted to project into the axial opening, and a tapered body that functions as a tip permanently fixed to the lower end of the tube and adapted to abut without interfitting with the pencil body.

2. In combination, a pencil body having an axial opening, one portion of which is non-circular in cross section, the lower end of the body being tapered, a slightly bowed threaded tube and a plunger adapted to project into the axial opening, and a tapered body, that functions as a tip permanently fixed to the lower end of the tube and adapted to abut without interfitting with the pencil body, said tip and tube being rotatable on said body.

3. In combination, a pencil body having an axial opening, one portion of which is non-circular in cross-section, the lower end of the body being tapered, a slightly bowed threaded tube and a plunger adapted to project into the axial opening, and a tapered body that functions as a tip having a conformation at its upper end substantially that of the tapered end of said body permanently fixed to the lower end of the tube and adapted to abut without interfitting with the pencil body.

4. In combination, a pencil body having an axial opening, one portion of which is non-circular in cross-section, the lower end of the body being tapered, a slightly bowed threaded tube and a plunger adapted to project into the axial opening, and a tapered body that functions as a tip permanently fixed to the lower end of the tube and adapted to abut without interfitting with the pencil body, said tip and tube being retained in said axial opening by reason of the contact of the bowed portion of said tube against the walls of the circular portion of said opening.

5. In a pencil comprising a barrel, a tip therefor at the writing end having a tapered portion, and a reduced sleeve portion rotatively engaged in said barrel, said sleeve being of yieldable material formed with a portion 65 thereof initially bent slightly out of true ax-

ial alignment, whereby to insure frictional resistance to its rotation when entered in the barrel.

In testimony whereof I have affixed signature.

FRANK C. DELI.
